Attorney

UNITED STATES PATENT OFFICE.

WALTER T. NORVELL, OF MORRILL, NEBRASKA.

MAIL-BOX SUPPORT.

1,281,062.

Specification of Letters Patent.

Patented Oct. 8, 1918.

Application filed September 11, 1917. Serial No. 190,768.

To all whom it may concern:

Be it known that I, WALTER T. NORVELL, a citizen of the United States, residing at Morrill, in the county of Scotts Bluff and 5 State of Nebraska, have invented new and useful Improvements in Mail-Box Supports, of which the following is a specification.

The invention relates to improvements in supports for mail boxes, and seeks to provide as its principal object a durable, efficient and simple device of this character, particularly serviceable on rural free delivery routes.

As a further object, provision is made for 15 means to permit the device to be used for holding boxes of various heights.

Other objects will appear in the detailed description which follows:

In illustrating the invention, a specific 20 form has been adhered to, but to this particular form the invention is not to be restricted. The right is reserved to make any changes or alterations suggested by an actual reduction to practice, if such changes or alterations are comprehended in spirit by the 25 appended claim.

In the accompanying drawings:—

Figure 1 is a perspective view of the invention, showing the latter holding a general 30 mail box.

Fig. 2 is a top plan view.

Fig. 3 is an elevation looking at that side of the box obscured in Fig. 1.

Referring to the drawings, 1 is a post 35 which may be made of any suitable material (preferably steel or iron) and this post is triangular in cross section, having affixed to it near its lower end the triangular plates 2 which are secured one to each of the three 40 sides of the post. The free corners of these plates 2 project beyond the sides of the post, and when the latter is buried in the ground and the dirt firmly tamped around it, these projecting corners offer an extra resistance 45 to any force tending to knock the post over.

Near the upper end of the post 1, an angular brace 3 is attached by rivets or other suitable means. This brace consists of the horizontal leg 4, and the diagonal leg 5 which are 50 integrally connected together at the ends remote from those attached to the post.

Riveted at their longitudinal centers to the horizontal leg 4 and positioned transversely thereon, so that they will lie in a horizontal plane, there are clamping members 6. These clamping members have their ends formed to provide ears 7. Coöperating with the clamping members 6 are the clamping members 8. These members 8 are U-shaped, and have their legs terminating in 60 ears 9 which are similar to ears 7. Both the ears 9 and ears 7 have holes at their centers and through these holes bolts 10 pass, the latter receiving on their threaded ends the nuts 11. By means of these bolts, the 65 clamping members 8 are attached to the clamping members 6, the heads of the bolts abutting the ears 9 and the nuts 11 abutting the ears 7. The clamping members 8 straddle the mail box 12 and, when the pair of 70 clamping members are secured together by the bolts 10, the mail box 12 is securely held in place. This mail box 12 is intended to be of any conventional form, being provided with the usual pivotally mounted apron on 75 the front, which may be raised to permit mail to be inserted into the box and being provided at the back with a door 14 which may be opened to permit the removal of mail from the interior of the box. A suitable 80 locking means 15 is provided for the door 14.

The manner of attaching the mail box is obvious in the disclosure in the drawings, and it is also obvious that the height of different boxes attached to the support may 85 vary greatly without requiring any modification of the attendant parts of the support, the bolts 10 permitting the clamping members 6 and 8 to be varied in their distances from each other to suit any height of box 90 within reasonable limits.

What is claimed is:—

In a device of the kind described, a supporting post, a supporting brace attached to the post near its top, the supporting 95 brace being of angular shape and having a horizontal leg and a diagonally disposed leg both of which are attached to the post in spaced relation to each other, flat clamping members secured to the horizontal leg and positioned transversely thereon so that they lie in a horizontal plane, the 100

ends of the said clamping members being formed to provide ears, U-shaped clamping members formed with ears at the termini of their legs, the ears of both clamping members being formed with holes, and bolts securing the U-shaped clamping members to the flat clamping members, said bolts pass-

ing through the holes in the ears of said clamping members, whereby coöperating clamping members may be varied in their positions relative to each other so that mail boxes of various heights may be held thereby.

In testimony whereof I affix my signature.

WALTER T. NORVELL.
